END CLOSURE FOR PAPERBOARD CONTAINERS

Lewis C. Brooks, Milwaukee, Wis., assignor of
one-third to Ira Milton Jones, Milwaukee, Wis.

Application March 12, 1945, Serial No. 582,385

2 Claims. (Cl. 229—5.5)

1

This invention relates to closures for containers and is a continuation in part of the co-pending application of Lewis C. Brooks, Serial No. 518,991, filed January 20, 1944, now Patent No. 2,398,405, issued April 16, 1946.

In the aforesaid application the container illustrated is made of paper board and the shoulder construction at the mouth of the container and which supports the closure is produced through a novel manner of folding the blank from which the body of the container is made. A flat disc secured on this shoulder and having an aperture larger than the mouth of the container at said shoulder so as to leave a ledge at the inner marginal portions of the shoulder cooperates with the ledge to securely hold the closure in place sealing the open top of the container. The closure includes a sealing sheet disposed over the disc and wedged into the aperture of the disc and onto the ledge by a relatively stiff insert bonded to the sealing sheet and of a size to snugly fit the disc aperture.

While this construction is admirably suited for containers made of paper board and the like, it is possible to embody the invention in a construction wherein the stepped-down inwardly projecting ledge is formed integrally with the body of the container at the mouth thereof. For instance, the container body might be molded of glass, pulp, or plastic, and it is one of the objects of this invention to provide a simple but efficient and positive unitary sealing closure for such molded containers.

More specifically it is an object of this invention to provide an inexpensive sealing closure for the open tops of molded or glass containers having flat upright side walls and convenient for packaging milk, dairy foods, and other products, and which in addition to sealing the mouth of the container acts to protect the rim of the container at the mouth against contamination.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

2

Figure 1 is a fragmentary perspective view of the top portion of a molded container particularly adapted for packaging milk, dairy or other products, and showing the sealing closure of this invention applied thereto;

Figure 2 is a fragmentary cross sectional view through a side wall portion of the container at the mouth thereof;

Figure 3 is a perspective view of the sealing closure viewing the same from the top side thereof and before its application to the mouth of the container;

Figure 4 is a view similar to Figure 1 but illustrating a slightly modified form of closure for the container mouth;

Figure 5 is a view similar to Figure 3 illustrating the top side of the closure shown in Figure 4, before its application to the container mouth;

Figure 6 is a view similar to Figures 3 and 5 illustrating a still further modified type of sealing closure; and

Figure 7 is a fragmentary perspective view of the upper portion of a molded container illustrating the closure of Figure 6 applied thereto.

Referring now more particularly to the accompanying drawings in which like numerals indicate like parts, the numeral 10 designates the body of a container of the molded type suitable for the packaging of milk, dairy foods, and other products.

While these molded containers have been made round in the past it has been recently recognized that the adoption of a square cross section results in a saving of substantial storage space and permits considerable reduction in the sizes of crates and cartons employed in shipping such containers. However, where square flat sided containers have been used the conventional round restricted neck designed to take the conventional bottle caps and covers was retained. As a result, these flat sided containers were undesirable because of the inconvenience and difficulty attending the removal of semi-solid food products through the restricted necks of such containers. This objection has in the past dissuaded the packaging of other than liquid food products in the flat sided containers.

The container of this invention, however, distinguishes from past containers in that it is provided with flat side walls defining a uniformly square or rectangular cross section throughout the entire depth of the container and terminating in a more or less flat rim 11 at the upper full open end or mouth of the container.

A stepped-down ledge 12 formed integrally

with and projecting inwardly from the side walls of the container around the entire inner periphery of the mouth thereof adjacent to the rim 11 provides a supporting surface 13 spaced a slight distance beneath the top of the rim 11 for the sealing closure 14 of this invention.

The sealing closure 14 comprises a relatively thin flexible sealing sheet 15 placed across the open mouth of the container so as to cover the rim 11 thereof and wedged into place covering the container mouth by a stiff insert or disc 16 to which it is bonded and of a size and shape to snugly fit the sides of the rim above the ledge 12 without projecting above the top of the rim 11. Although the insert 16 does not project above the top surface of the rim 11 it nevertheless serves to tightly press the sealing sheet 15 down onto the supporting surface 13 of the ledge and against the sides of the rim to form a secure joint at the mouth of the container.

As clearly illustrated in Figure 3, it will be seen that the sealing sheet 15 is bonded to the insert 16 prior to application of the closure to the mouth of the container and this is preferably effected by means of a permanent adhesive.

The underside of the flexible sealing sheet is adhered to the supporting surface 13 of the ledge, the top of the rim 11 to protect the same against contamination, and the inner sides of the rim adjacent to the ledge by means of a repeatedly effective pressure sensitive adhesive. Such an adhesive enables the marginal portions of the sealing sheet to be repeatedly lifted to uncover the container mouth and reapplied to seal the container mouth a number of times at will.

The adhesive employed for this purpose may consist in a synthetic wax with strong adhesive qualities, for example, or may be of the type commonly used on "Scotch tape" whose effectiveness for repeated use as a sealing medium is well known.

The act of uncovering the container mouth is facilitated by means of an extension of one side edge of the sealing sheet 15 forming a pull tab 17 normally adhered to one of the outer side walls of the container by the same repeatedly effective pressure sensitive adhesive in the closed position of the cover. The portion of the strip 15 opposite the pull tab may, obviously, serve as a hinge by its adhesion to the rim 11 during uncovering of the mouth of the container.

If desired, the sealing sheet 15 may be provided with flanges 18 integral therewith as shown in Figures 4 and 5 to extend around the top of the rim 11 and to overlie the sides of the container to afford better protection against contamination of the exterior surfaces of the container over which its contents is likely to be dispensed and to afford better protection against accidental displacement of the closure. These flanges are likewise adhered to the outer side walls of the container by a repeatedly effective pressure sensitive adhesive of the type previously described, and any one of the flanges may serve as a pull tab in opening the container.

In place of the repeatedly effective adhesive sensitive to pressure alone, it may be advantageous in some instances (depending upon the type of goods packaged) to employ a special adhesive sensitive to or activated by both heat and pressure for attachment of the sealing closure of this invention to the mouth of the container. Certain synthetic waxes applied to the closure, one of which is known to the trade as "Flexo C-Light," have such characteristics as

to enable the closure to be sealed in place with a tenacity depending upon the degree of heat employed, in combination with pressure, during application of the closure to the container mouth.

When the proper degree of heat is employed in the initial sealing operation, such an adhesive acts to securely hermetically seal the container mouth and to afford ample protection against accidental displacement of the closure during handling of the filled container, but permits the closure to be lifted in the hereintofore described manner to uncover the container mouth for dispensing of the container contents. Also, this particular type of adhesive permits resealing of the closure after partial dispensing of the container contents merely by the application of pressure alone; the adhesive thus becoming repeatedly pressure sensitive after initial opening of the closure to allow resealing of the container a number of times at will.

For molded containers of the type shown and which are repeatedly refilled by the producer, the degree of heat employed with pressure in initially sealing the closure would obviously be less than for paper board containers or others of the molded type used once and then discarded.

Some molded containers, especially those for milk, require thorough washing and cleansing and a permanent bond between the sealing closure and container mouth must be avoided. If preferred, however, one marginal edge or flange of the closure which is to act as a hinge may be sealed to the rim or outer side wall of the molded container with a greater tenacity than the remaining portions of the closure by the application of slightly more heat to said edge or flange so as to prevent accidental removal of the entire closure during opening of the container.

As will be apparent, this same type of adhesive is equally desirable for sealing the end closure of this invention to paper board containers having similarly designed mouth and of the type shown and described in the aforementioned copending application of Lewis C. Brooks, Serial No. 518,991, filed January 20, 1944. When so employed, it is possible to bond the portion of the sealing sheet which is to act as a hinge permanently to the container by the application of a suitable high degree of heat (and pressure) thereto during initial sealing. Permanent sealing of the hinged edge is, of course, also possible with such molded or glass containers as are used once and then discarded.

Inasmuch as the sealing sheet is preferably adhered tightly to the container mouth with this synthetic wax adhesive so as to enable hermetic sealing of the container contents, the sealing sheet must in all cases be stronger than the sealed joint to enable the joint to be broken without improper tearing of the sheet.

When a flanged closure is employed, it may also be desirable to provide the flexible sealing strip 15 with perforations 19 along opposite side edges thereof at the bend line of the flanges as shown in Figures 6 and 7 and along which the cover may be conveniently torn open. One side 20 of the sealing strip is preferably left imperforate so that it may act as a hinge for the closure disposed either on the top surface of the rim or upon the outer rear side wall adjacent thereto upon tearing of the strip along its perforations 19 to uncover the container mouth as illustrated in Figure 7.

When such perforations are used, the flange opposite the side 20 may be imperforate to act

as a pull tab or a special pull tab 21 may be provided thereon. This tab 21, as shown in Figure 7, is formed by a central imperforate section of the flange 18 opposite the hinge 20 having perforations 22 along its side edges leading from perforations 19 similar to the perforations 19 to the free edge of the flange.

The tab 21 facilitates opening of the cover inasmuch as it merely requires loosening of a small portion of the flange from the side wall to which it is adhered to enable tearing of the strip along its perforations in the manner hereinbefore described. Obviously, the outer edge portion of the tab 21 may be left free of the container side wall to facilitate grasping the same.

From the foregoing description taken in connection with the accompanying drawings, it will be readily apparent to those skilled in the art that this invention provides an improved unitary closure for molded or glass containers having flat side walls which may be lifted and reapplied in a sealing capacity repeatedly so as to enable the contents of the container to be fully protected in the periods between dispensing of the contents.

What I claim as my invention is:

1. A full opening end closure construction for the mouth of a multiple sided container having rigid side walls comprising: a ledge integral with the side walls of the container and spaced down from the end thereof, said ledge extending entirely around the inner periphery of the mouth of the container; an insert of a size to fit snugly into the mouth of the container so as to rest on said ledge; a thin, flexible sealing sheet adhered to the underside of said insert and projecting beyond the edges of the insert; a repeatedly effective pressure sensitive adhesive on the underside of said sheet by which the marginal portions thereof are removably adhered to the ledge and the wall surfaces defining and adjacent to the mouth of the container, said sheet being squeezed between the edges of the insert and the adjacent side wall surfaces, and the repeatedly effective pressure sensitive characteristics of the adhesive on the underside of the sealing sheet enabling reclosing of the container mouth after initial opening; side flanges on said sealing sheet folded over the adjacent portions of the sides of the container; and repeatedly effective pressure sensitive adhesive on the undersides of said flanges by which they are adhered to the side walls, said thin sealing sheet being weakened at the junctures of the side flanges to the sheet proper along all but one of the sides, but with its line of weakness at the juncture of the flange opposite said one side interrupted for a distance and with the line

of weakening turned outwardly to the edge of the flange to define a pull tab so that lifting of said tab and the application of force thereon tears the sealing sheet along its lines of weakness and leaves the closure hinged to the side of the container opposite the pull tab.

2. A full opening end closure construction for the mouth of a multiple sided container having rigid side walls comprising: a ledge integral with the side walls of the container and spaced down from the end thereof, said ledge extending entirely around the inner periphery of the mouth of the container; an insert of a size to fit snugly into the mouth of the container so as to rest on said ledge; a thin, flexible sealing sheet adhered to the underside of said insert and projecting beyond the edges of the insert; a repeatedly effective pressure sensitive adhesive on the underside of said sheet by which the marginal portions thereof are removably adhered to the ledge and the wall surfaces defining and adjacent to the mouth of the container, said sheet being squeezed between the edges of the insert and the adjacent side wall surfaces, and the repeatedly effective pressure sensitive characteristics of the adhesive on the underside of the sealing sheet enabling reclosing of the container mouth after initial opening; side flanges on said sealing sheet folded over the adjacent portions of the sides of the container; and repeatedly effective pressure sensitive adhesive on the undersides of said flanges by which they are adhered to the side walls, said thin sealing sheet being weakened at the junctures of the side flanges to the sheet proper along all but two opposite sides so that one of said unweakened sides provides a hinge for the closure while the flange opposite thereto provides a pull tab so that the application of force thereon tears the sealing sheet along its lines of weakness and leaves the closure hinged to the sides of the container opposite the pull tab.

LEWIS C. BROOKS.
